BANDING MACHINE

Clarence J. Keller, Anderson, Ind., assignor to
 General Motors Corporation, Detroit, Mich., a
 corporation of Delaware

Application August 1, 1940, Serial No. 349,209

16 Claims. (Cl. 153—1)

This invention relates to the manufacture of electrical wiring devices and more particularly to devices for wiring or electrically connecting the electrically operated accessories on an automobile. Such a wiring device for automobile use is generally known as a wiring harness; and it consists of a bundle of two or more wires provided at their ends with suitable terminals.

One method of bundling together a group of wires is to weave or braid a fabric sheath around the bundle of wire. I propose, however, to secure the wires together by means of metal bands which are bent around the wires, the insulation of the wires being protected by the interposition of a non-metallic, insulating liner band between the insulation of the wires and the metal band. Accordingly it is an object of the present invention to provide a machine into which strip liner material and metal are fed and cut off to provide insulating and metal band of the required length and by which the insulating band is placed upon the metal band and both together are folded into U-shaped formation within a workholder preparatory to receiving a bundle of electrical wires. The work holder containing portions of the wires received within the U-shaped liner and metal bands is transferred by a conveyor to a station where the up-standing flanges of the liner and metal bands are folded down against the insulated wires to secure them together.

Further objects and advantages of the present invention as herein disclosed, will be apparent from the following description, reference being had to the accompanying drawings wherein a preferred form of the invention is clearly shown.

In the drawings:

Fig. 1 is a perspective view of a bundle of two electrical wires secured together by a metal band or strip overlying an insulating band.

Figs. 2 and 3 taken together constitute a fragmentary side elevation of a machine for forming insulating and metal band from strip material and for holding them around a bundle of wires as shown in Fig. 1. The sectional part of Fig. 3 is on the line 3—3 of Fig. 5.

Figs. 4 and 5 taken together constitute a fragmentary front view of the machine, the sectional part being taken on the line 5—5 of Fig. 3.

Fig. 4a on the same sheet with Fig. 4 is a front elevation of a fragment of the upper left-hand part of Fig. 4 and shows certain moving elements in their respective positions after the crank shaft of the machine is rotated 180°.

Fig. 6 is a fragmentary view taken along the line 6—6 of Fig. 3 and shows the top view of

the upper die block as if it were detached from the press head.

Fig. 7 is a fragmentary view taken in the direction of the arrow 7 of Fig. 6.

5 Fig. 8 is a sectional view on the line 8—8 of Fig. 5.

Fig. 9 is a view on the line 9—9 of Fig. 8, omitting the punches shown in Fig. 8.

10 Fig. 10 is a sectional view on the line 10—10 of Figs. 6 and 8 showing the punches down as in Fig. 8.

Fig. 11 is a sectional view on the line 11—11 of Fig. 6 and shows the punches up.

15 Fig. 12 is a sectional view on the line 12—12 of Figs. 6 and 8, with the punches up.

Fig. 13 shows diagrammatically in perspective the shearing and forming punches of the machine in relation to the insulating and metal bands and to the work holder.

20 In building the wiring harness banding machine in accordance with the present invention, I start with a suitable punch press of standard make comprising the usual bed 20 (Fig. 5) mounted on legs 21 and supporting frames 22

25 providing guides 23 for a press head or ram 24 (Fig. 4). Ram 24 is vertically movable and is connected by a ball and socket connection indicated at 25 with a connecting rod 26 connected with crank pin 27 integral with crank arms 28

30 provided by a crank shaft 29 journalled in bearings provided by brackets 30 which are attached to the frame 22. Shaft 29 drives a barrel cam 31 having a groove 32 receiving a roller 33 attached to a lever 34 pivoted at 35 on a bracket 36 attached to the frame 22. The lower end of lever 34 (Fig. 5) is pinned at 37 to an adjustable link 38. Through the left end of link 38 there passes a bolt 39 also passing through a slot 40 in a lever 41. The angular movement of

40 lever 41 relative to the angular movement of lever 34 can be adjusted by varying the position of the bolt 39 relative to the slot 40. When the bolt 39 is in the proper position it is fixed in that position by tightening a nut 42.

45 Lever 41 is pivoted at 43 upon a pair of brackets 44 fixed to a plate 45 attached to a table 46 mounted on the bed 20 of the punch press. The plate 45 supports a bracket 47 which supports rods 48 along which slide a device 50 connected by a link 49 with the roll end of lever 41. The device 50 is what is known as a sliding feed and may be of any well-known make such as the "U. S. slide feed." As this device is not

50 per se a part of the invention its detail construction is not shown. For present purposes it

is sufficient to state that the slide feed 50 reciprocates left and right upon the rods 48 (Fig. 5). When it moves toward the right it moves with a liner strip P (preferably insulating paper) which is guided by a grooved plate 51 mounted on a bracket 52 attached to the bracket 47. When the slide feed 50 moves toward the left it releases its grip upon the paper P, which remains stationary until the slide feed moves to the right again. The paper strip P is therefore fed from the left side toward the center of the machine as viewed in Fig. 5.

The metal strip S (preferably of steel) is fed from the rear of the machine to the center or toward the observer as viewed in Fig. 5, or from right toward left as viewed in Fig. 8. The steel strip, like the paper strip, is unwound from a supply roll and is fed intermittently by another slide feed (Fig. 3), similar in construction and mode of operation to the slide feed 50. The device 60 slides on rods 61 mounted on the bed 20 of the punch press. As the slide feed 60 moves toward the right (Fig. 3) it causes the movement of the metal strip S which is guided horizontally by grooved plate 64 secured by bracket 65 to the bracket 62. The slide feed 60 is reciprocated by a mechanism comprising a link 70 connecting it with a bell crank lever 71 pivoted at 72 on bracket 73 attached to bracket 62. Lever 71 is connected by pin 74 with adjustable link 75 connected by pin 76 (Fig. 2) with an arm 77 adjustable radially with respect to an arm 78 pinned to shaft 79. Shaft 79 is connected with a lever arm 80 pinned at 81 to an adjustable link 82 connected with a strap 83 which is apertured at 84 to clear the hub 85 of a double cam having a cam plate 86 for engaging a roller 87 pivoted by a screw 88 on the strap 83. The other plate 90 of this cam engages roller 91 pivotally mounted on the strap 83. Rotation of the crank shaft will effect reciprocation of the strap 83 and rod 82 and the oscillation of levers 80, 78 and 71 to effect reciprocation of the slide feed 60.

Referring to Fig. 13, it will be seen that the metal strip S is fed in the direction of the arrow 100 toward a central part of the machine and vertically above a workholder comprising a grooved block 101 located between two vertical pins 102. A punch 103 shears the strip S at the line 104. After the shearing operation the strip S continues to be fed and pushes the severed strips S' also in the direction of the arrow 100. The distance through which the strip S is fed each time is such that there will be one strip S' located between the shearing line 104 and that strip S' located vertically above the work holder block 101. The length of each strip S' is less than the width of the paper strip P so that the ends of paper strip P' will extend beyond the ends of the strip S'. The width of the paper strip P' is greater than the width of the metal strip S'. When the strips S' and P' are formed around the wires 224 and 225 (Fig. 1), no part of the strip S' is in contact with the insulation of these wires. Fig. 13 shows that the paper strip P is fed in the direction of the arrow 105 which, in a plan view would be at right angles to the arrow 100. Between the operations of intermittently feeding the strip P, it is sheared almost across by a punch 106 which cuts the paper at the lines 106a, thus leaving a small neck at 106b which is not severed. The shearing punch 106 therefore shears the paper into band liner portions P'. The extent of feed of the paper P is such that there will be two sections P' between 78 and 135 and the metal strip guide channel 114

the shearing lines 106a and that portion P' which is vertically above the work holder block 101. The mechanisms which feed the strips S and P are so timed that the metal strip S' arrives over the work holder block 101 (Fig. 13) ahead of the strip P'. This is desirable since it is necessary that the strip P' rest upon the strip S'. This might not happen if the strip P' were to arrive over the block 101 ahead of the strip S'. The function of the punch 107 (Fig. 13) is to force the superposed strips S' and P' into U-shaped formation upon the block 101 and between the pins 102 as shown in Fig. 8. The punches 103, 106 and 107 are fastened to a plate 110 secured 15 to the press ram 24 (Fig. 8).

The punch 103 is vertically above an opening 111 in a plate 112 which provides a cover for a plate 113 having groove 114 therein for receiving the strip S. Plates 112 and 113 are mounted 20 upon the block 143 which is supported by table 46. A portion of the groove 114 is blocked by a stop strip 115 (Fig. 8) which limits the movement of the strip S in the direction of the arrow 100 (Fig. 13) or toward the right in Fig. 8. Initially, the mechanism for operating the slide feed 60 will be adjusted so that the strip S' will just engage the stop 115. After that the feed 60 will feed the strip S' into the correct position under punch 107. The punch 103 is provided 25 with a cutting edge 116 which cooperates with a shearing surface 117 provided in plate 113 in order to cut the strip S along the line 104 (Fig. 13). The punch 103 is provided with tangs 118 received by grooves 119 in a block 120 which is 30 vertically slidable in a recess 121 provided by block 143. A spring 122 urges the block 120 upwardly so that its flanges at 120a may strike against the lower surface of the plate 113. The punch 103 carries with it a rod 125, the lower 35 end of which is adapted to engage the strip S and clamp it to block 120 while the cutting edge of the punch 103 shears the strip as shown in Fig. 8. When the press head 24 moves upwardly to carry the punch 103 and the rod 125 away 40 from the plate 112, then the strip S will be forced upwardly against the upper side of the plate 112 by the spring pressed block 120 which thereby aligns the left edge of the uncut strip S with the 45 cut portion S' further to the left in the channel 50 114.

The punch 106 is vertical above an aperture 130 in the plate 112. Punch 106 is provided with oblique cutting edges 106 which cooperate with left hand surfaces 131 defining a recess 132 in block 113 (Fig. 10) to shear the paper strip P along the lines 106a. The recess 132 receives a block 133 which is cut away to provide inclined surfaces 134 and thus provide clearance for the cutting edges 106x of the punch 106. These oblique surfaces 134 guide the strip section P' to a horizontal groove 135 provided between the plates 112 and 113 for the purpose of guiding the liner strip P' into location above the metal band S' after it arrives above the workholder block 101. That portion of the channel 135 which lies to the right of the punch 107 (Fig. 10) is blocked by a stop-plate 136 which limits travel of the strip P' to the right of the lower end of the punch 107. Initially, the mechanism for operating the slide feed 50 will be adjusted so that the strip P' will just engage the stop 136. After that the feed 50 will feed strips P' into the correct position under punch 107.

Referring to Fig. 9 the paper strip guide chan-

cross each other below an aperture 140 in plate 112. Plate 113 is provided with an aperture 141 which cuts across the channel 114 and which is located midway between the edges of channel 135. Aperture 141 is in vertical alignment with aperture 140 and with punch 107 and also in vertical alignment with aperture 142 in block 143. The aperture 142 is in alignment with aperture 144 in a hard metal insert 145 secured to block 143 by screws 146. The aligned apertures 141, 142 and 145 are of such width as to receive the strips S' and P' when they are forced downwardly by the punch 107 and are caused thereby to take a U-shaped formation as shown in Fig. 8 and finally to be located upon that workholder block 101 which is then vertically below the punch 107. When the punch 107 is pulled upwardly by the press ram 24, and strips S' and P' are retained by frictional engagement with the pins 102 associated with the block 101. If they tend to pull out with the punch 102 they will also tend to spread out and their upper edges will be caught against the insert plate 145 which therefore serves as means for stripping the strips from the lower end of the punch 107.

During the downward movement of the punch to carry the strips from the flat condition shown in Fig. 13 into the U-shaped formation shown in Fig. 8, that paper strip P' then under the punch is severed from the adjacent strip P' due to the cooperation of the punch 107 with the edge 141 x defining the aperture 141.

After the ram 24 moves upwardly to withdraw all of the punches from the channels which guide the paper and metal strips and before the punch returns downwardly to cross these channels, the slide feeds 50 and 60 are operated in order to move other paper strips P' and other steel strips S' into position between the punch 107 and a vertically aligned workholder block 101.

There are a plurality of workholder blocks 101 each mounted together with pins 102 on a plate 150. The plates 150 are all connected by chain links 151, thus providing an endless chain conveyor. There are two chains of links 151 which pass around a pair of idle sprocket wheels 152 near the front of the machine and a pair of driving sprocket wheels 153 located toward the rear of the machine. The sprocket wheels 152 are mounted on a shaft 154 journalled in bearings 155 provided by brackets 156 fastened by screws 157 to the table 46. Table 46 supports guide bars 160 and 161 for guiding the chains 151 and the blocks 150. The block 143 is provided with a channel 143a to provide clearance for the blocks 101 and pins 102. The guide plate 160 which is set into a recess 160a in the table 46 provides a rest or support for the blocks 101 as they pass through the channel 143a of block 143.

As viewed in Fig. 8, these blocks 101 move toward the left and are propelled in this direction by an intermittent motion which comprises a bar 170 guided for vertical sliding movement by brackets 171 fixed in bed 20 (Fig. 3) and carrying a pawl 172 urged by spring 173 into engagement with a ratchet 174 which is drivingly connected with one of the pair of sprockets 153 which, together with the other sprocket 153 is mounted on a shaft 175 journalled in bearings 176 provided by side frames 22 (Fig. 6). Rod 170 is connected by pin 180 with a bar 181 fixed to a rod 182 extending through a plain hole 183 in a bar 184 fastened by screws 185 to ram 24. During upward movement of ram 24 from the bottom shown in Fig. 8, lost motion is taken up

between the bar 184 and nuts 186 adjustably secured to the rod 182. When this motion is taken up, further upward movement of the ram 24 causes the rod 182 and hence the bar 170 (Fig. 5) to be lifted, thereby causing the pawl 172 to rotate the ratchet 174 through a predetermined angular distance for the purpose of causing the chains 151 to move clockwise around the axis of shaft 175 and thus move the upper workholder blocks toward the right (Fig. 3) and toward the left (Fig. 8). By adjusting the position of the nuts 186 on the rod 182 (Fig. 8) to adjust the amount of lost motion between the ram 24 and the ratchet mechanism which drives the chain 151, the travel of the chain conveyor can be adjusted so that it will move each time a distance equal to the spacing of the blocks 101. During downward movement of the ram 24, the bar 184 will engage spring 187 to move the bar 170 downwardly with yielding pressure to force the lower end of the bar 170 against a stop screw 190 located in adjusted position with respect to a bracket 191 by a lock nut 192. During downward movement of the bar 170 the pawl 172 drags along the ratchet 174 which is prevented from rotation by virtue of a brake associated with the shaft 175. This brake comprises a drum 200 (Fig. 7) engaged by brake band segments 201 carried by clamping members 202 which are fulcrumed about a stud 203 secured to frame 22 and retained by nut 204. The friction segments 201 are clamped against the brake drum 200 with pressure effected by the tightening of a nut 205 of a screw 206 which passes through the clamping members 202.

35 The transmission of motion from a rotary driving wheel to the punch crank shaft 29 is effected through a one-revolution clutch (not shown) controlled in the usual manner by pressing a pedal or other suitable operating member.

40 When the clutch closes, the press ram moves from top-most to lower-most position and then returns to the top-most position and then the rotation of the shaft 29 stops. As the conveyor chain 121 moves the workholders filled with

45 U-shaped paper and steel strips toward the left (Fig. 8), a workholder thus filled will arrive under a forming punch 210 slidably supported by a block 211 and the plate 110. The upper end of punch 210 is welded to a plate 212, the position of which is controlled by a cam 213 fastened to a shaft 214 by a key 215 and a set screw 216. Shaft 214 is journalled in bearings provided by plates 217 fastened by screws 217a (Fig. 6) to plate 110. Plate 110 is reinforced by

50 block 218 fastened by screws 219 to the ram 24 and by screws 219a to plate 110. Plungers 220 urged upwardly by springs 221 urged the plate 212 against various surfaces of the cam 213. These surfaces are of different distances from the center of shaft 214. Therefore, by turning the shaft 214, the relation between the upper end of the punch 210 and the ram 24 can be varied to accommodate variations in the number or thickness of the wires which are to be banded together by the strips P' and S' as shown in Fig. 1. For the purpose of adjusting the punch 210 vertically relative to the workholder 101, the shaft 214 can be rotated by turning a handle 222 attached thereto. The lower end of the punch 210 is provided with a notch 223 of such formation as to engage the up-standing ends of the liner strip and banding strip and to cause them to be folded around the wires 224 and 225 as shown in Fig. 8, in order to band the wires together as shown in Fig. 1.

55

60

65

70

75

During downward movement of the punch 210 it straddles the block 101 and pushes the adjacent pins 102 downwardly thus forcing them against a plunger 230 supported by compression spring 231 housed within a tubular bracket 232 closed at its lower end by plate 233 and fastened at its upper end to the underside of table 46. When the punch 210 moves upwardly the pins 102 are returned to normal position by the spring 231 acting upwardly on the plunger 230 which returns its upper surface into the plane of the upper surface of the plate 160, the flange 230a of the plunger 230 then striking against the shoulder 232a of the bracket 232.

To operate the machine, the operator sits in front of the machine as viewed in Fig. 8. He places a bunch of wires in the recess or notch provided by the U-shaped banding strips P' and S' then located by workholder under the punch 210. Then he presses a pedal to cause the punch ram to descend, thereby causing the punch 210 to form the strips S' and P' around the bundle of wires and thus banding them together. During this operation the workholder under the punch 107 is being filled with U-formed strips of paper and steel. The workholder between the punches 210 and 107 has already been filled with U-shaped banding strips. During the upward movement of the press ram 24 to carry the punch 210 out of engagement with the strips which have just been operated upon to band a bundle of wires together, the conveyor chain 151 moves counterclockwise as viewed in Fig. 8 to bring the next succeeding workholder filled with U-formed strips under the punch 210. Then the press stops with the punch 210 in uppermost position and a filled workholder vertically below it. The operator may then place the same or a different bundle of wires within the groove provided by the U-formed strips then vertically below the punch 210 and trip the press again to repeat the banding operation upon the same or a different bunch of wires.

It is apparent from the foregoing description of the construction and mode of operation of the machine that the machine provides for cutting off the banding strips of paper and steel from strip stock, for placing these strips in superposed relation, for forming the strips into U-form with the paper strip inside the steel strip, for transferring these U-strips from the first forming station to a second forming or banding station where the operator places within the groove provided by them a group of wires to be banded together. At this second forming station a punch descends to deform the banding strips around the group of wires so as to secure them as a bundle for convenient handling.

If insulation coated banding metal strip stock is used, the machine can be operated without the strip paper feeding means. Obviously the present machine will operate upon a non-insulated metal banding strip, without a liner strip, if such metal strip could be used in direct contact with the insulation of the wires, the kind or amount of insulation of the wires being such that there would be no likelihood of short circuit.

While the embodiment of the present invention as herein disclosed, constitutes a preferred form, it is to be understood that other forms might be adopted, all coming within the scope of the claims which follow.

What is claimed is as follows:

1. A machine for banding a group of insulated wires comprising means for supporting a metal

banding strip and a banding strip liner of non-conducting material in juxtaposed relation, means for forming the strips into U-formation with the liner strip inside the metal strip, a work-holder for receiving the U-strips as formed by the forming means, means for moving the work-holder relative to the supporting means, and a second forming means cooperating with the work-holder in another position thereof for bending the branches of the U-strips toward a group of insulated wires placed within the confines of the U-strips.

2. A machine according to claim 1 in which the first forming means comprises a punch cooperating with a die opening in the strip supporting means.

3. A machine according to claim 1 having means for moving the work holder from the first forming means to the second forming means.

4. A machine according to claim 1 having an endless conveyor carrying a plurality of the work-holders and moved intermittently to carry the work holders containing U-strips from the first forming means to the second forming means.

5. A machine according to claim 1 having means for feeding lengths of strip metal and strip liner material and means for cutting the lengths of strip material to provide the banding strip and liner, the uncut material, when being fed, moving the cut material to the banding strip supporting means.

6. A machine according to claim 1 having means for feeding a length of strip metal in one direction toward the banding strip supporting means, means for feeding a length of strip liner material toward the banding strip supporting means in a direction transverse to the direction of movement of the first mentioned feeding means, and means for cutting the lengths of strip material to provide the banding strip and liner strip, the uncut material, when being fed, moving the cut material to the banding strip supporting means.

7. A machine for banding a group of wires comprising, means for feeding a length of strip metal and a length of band liner material into juxtaposed relation, means for cutting said lengths of strip material to provide the banding strip and liner strip, means supporting the banding strip and liner strip when in juxtaposed relation, means for forming the strips into U-formation with the liner strip inside the metal strip, a work holder for receiving the U-strips as formed by the forming means, a second forming means for bending the branches of the U-strips toward a group of wires placed within the confines of the U-strips, and means for moving the work holder from the first to the second forming means.

8. A machine for banding a group of insulated wires comprising, means for supporting a banding flat strip in straight condition, means for forming the strip into U-formation through an opening in the supporting means; a movable workholder for receiving the U-strap as formed by the forming means; means for moving the workholder in strips from the first position to other positions; a second forming means cooperating with workholder in one of said other positions for bending the branches of the U-strip to embrace the insulation of a group of wires placed within the confines of the U-strip.

9. A machine for banding a group of wires

comprising, stationary means for supporting a banding strip in straight condition, means for forcing the strips through an opening in the supporting means into U-formation, a workholder for receiving the U-strap as they pass through the opening; means for moving the workholder relative to the stationary supporting means and conveying the U-strap to another station remote from the receiving station; and a second forming means cooperating with the workholder in said other station for bending the branches of the U-strip toward a group of wires placed within the confines of the U-strip.

10. A machine according to claim 8 having means actuated in steps for moving the work holder step-by-step from the first forming means to the second forming means.

11. A machine according to claim 8 having an endless conveyor carrying a plurality of the work holders and moved intermittently to carry the work holders containing U-straps from the first forming means to the second forming means.

12. A machine for banding a group of insulated wire comprising means for feeding a metal banding strap in one direction and a non-conducting strap in another direction so that the straps will be in superposed and overlapped relation over a support having an opening; means for forcing the straps through the opening and forming the straps into U-shape with the non-conducting strap inside the metal strap, a workholder movable relative to the support and having a plurality of positions, said workholder receiving the U-straps as formed by the forming means in one position; means for moving the workholder to another position, and a second forming means for bending the branches of the U-straps around a group of insulated wires placed within the confines of the U-straps when said workholder is moved to one of its other positions.

13. A machine for banding a group of insulated wires together comprising, means for feeding a metal strap; means for severing a length from the strap, the uncut metal, when being fed, moving the severed length to a predetermined position; means for feeding a strap of insulating material over the severed length of metal; means for partially cutting the insulated strap into a liner for covering the severed length of metal; a punch for severing the liner over the length of metal from the strap of insulating material and for bending the severed length of metal and the severed liner in U-formation with the liner inside the metal length; a workholder for receiving the U-straps as formed by the punch; means for bending the branches of the U-straps around the insulation of a group of the wires placed within the confines of the U-straps; and means for moving the workholder from the first mentioned bending position to the second mentioned bending position.

14. A machine for banding a group of wires comprising, a die having an opening; means for feeding a metal banding strip and banding strip liner in different directions in juxtaposed relation and over the opening of the die; means for cutting the strips in lengths to provide the banding strip and liner; forming means comprising a punch cooperating with the die opening for forming the lengths into U-formation; workholders movable beyond the die for receiving the U formations; a second forming means comprising a punch cooperating with the workholders, for bending the branches of the U formations toward a group of wires placed within the confines of the U-formations; and means for intermittently shifting the workholder from the first forming means to the second forming means.
15. A machine for banding a group of insulated wires together comprising, a supply of flat metal strips; a supply of non-conducting strips; means for feeding the metal strip in one direction; means for severing a length from the metal strip, the uncut metal, when being fed, moving the severed length to a predetermined position; means for feeding the non-conducting strip in another direction and over the severed length of metal; means for severing a length from the non-conducting strip over the length of metal and for forming the severed lengths of metal and non-conducting material into U-formation; a workholder for receiving the U-straps as formed by the forming means in one position; means for intermittently shifting the workholder to other positions; and a punch cooperating with the workholder in one of its other positions for bending the branches of the U-straps around the wires placed within the confines of the U-straps.
16. A machine for banding a group of wires comprising, a stationary die having an opening; means for feeding a strip of metal in one direction relative to the die so that the end of the strip covers the opening; means for feeding a strip of non-conducting material relative to the die and in a direction transverse to the direction of movement of the first mentioned feeding means so that the end thereof covers the end of the metal strip; means for severing the ends of the strips to provide the banding and liner strips; a punch cooperating with the opening of the die for forming the severed strips into U-formation with the liner strip inside the metal strip; an endless conveyor carrying a plurality of workholders and moved intermittently to align the workholders with the die opening to receive the U-strip formation and also to move the workholders containing the U-straps past the die; and a second punch cooperating with the workholders for bending the branches of the U-straps around the group of wires placed within the confines of the U-strip.

CLARENCE J. KELLER.
